W. H. PAYNE.
Grain Binder.

No. 234,372.

Patented Nov. 9, 1880.

UNITED STATES PATENT OFFICE.

WILLIAM H. PAYNE, OF SANDWICH, ILLINOIS.

GRAIN-BINDER.

SPECIFICATION forming part of Letters Patent No. 234,372, dated November 9, 1880.

Application filed November 17, 1879.

To all whom it may concern:

Be it known that I, WILLIAM H. PAYNE, of Sandwich, in the county of De Kalb and State of Illinois, have invented a new and useful 5 Improvement in Grain-Binders, which is fully described in the following specification, reference being had to the accompanying drawings, in which—

Figure 1 represents a side elevation of a 10 grain-binder embodying my improvements; Fig. 2, a bottom plan of the revolving grain-table detached; Fig. 3, a plan view of the bed or support for the grain-table; Fig. 4, a vertical section through the table and support, 15 the binding-arm being depressed and the twisting mechanism in position for forming the twist in the band; Fig. 5, a detail section taken on the line $x-x$, Fig. 2, the mechanism being shown in idle position; Fig. 6, an end 20 elevation, on an enlarged scale, of the twister, cutter, and that portion of the grain-table to which they are attached; Fig. 7, a perspective view, on a similar scale, of the twister, cutter, and vibrating frame to which they are attached; Fig. 8, a perspective view of the 25 peculiar pinion on the grain-table, which operates the crank-shaft to vibrate the binding-arm at the proper intervals; and Fig. 9, a detail view, showing a portion of the band and the twist 30 which secures it around the bundle.

My invention relates to a grain-binder which is intended to be used in connection with a harvesting-machine wherein the grain is delivered to the binder intermittently or in gavels, instead of in a constant stream.

The invention consists, mainly, in the combination of a bed or support provided with rack-segments, a revolving grain-table, a binding-arm mounted in the table, and a crank-shaft provided with a pinion, the several parts 40 co-operating as hereinafter specified.

The invention also consists in certain devices and combination of devices whereby the required intermittent vibration of the binding-arm is effected as the grain-table revolves.

The invention also consists in certain peculiar band-fastening devices, whereby a peculiar twist is formed in the band-wire.

All of these parts will be hereinafter more 50 fully described, and will be particularly defined and pointed out in the claims.

In the drawings, A represents the bed or support for the grain-table, and is shown in the drawings of a circular form. The grain-table B is also of a circular form, and is mounted 55 by any suitable pivotal support on the bed-piece A in such manner that it may be revolved freely. The bed-piece A is secured to the framework of the harvester by any suitable means, and in such position as is required by the delivery mechanism employed in order to effect 60 the suitable delivery of the gavels upon the table. It is not necessary to describe these devices more particularly here, as they will be readily understood by those familiar with 65 grain-harvesting machines.

The bed A is provided with an upright flanged rim, a, running around its outer edge. A second upright flange, A', is arranged some distance within the outside rim, and is also circular in form. In the upper edge of this latter flange is a long cam-depression, a', and in the side thereof, just at the commencement of the former depression, is a short recess, a''. A driving-shaft, C, is mounted in suitable bearings on this bed, and is provided with a pinion, c, arranged within the flange A'. On the rim of the bed-piece, near the shaft C, is a short gear-segment, D, and on the other side of the rim, but not quite half-way round, is a similar 75 segment, D', while between the two is a circular rack, E, attached to the rim opposite to the depression a' in the flange A'. The rack E is on the inside of the rim, and projects above it, being inclined at each end, so as to 80 vanish at the rim, as shown in Fig. 1 of the drawings. It is also beveled or tapered at each end, and at the finishing end is cut away so as to form a notch, e, in the upper part thereof, as shown in Fig. 3 of the drawings. 90

On the bottom of the table B is a circular rack, b, with which the pinion c engages, thereby providing means for the revolution of the table. An upright standard, b', is mounted on the table near one side of the latter, and the band-spool b'' may be supported on the top of this standard, if desired. The binding-arm F is pivoted to this standard, being shown in the drawings arranged in a slot therein.

A pitman, G, is attached by a ball and socket or other suitable socket to the end of the binding-arm behind its pivot, and the

lower end of this pitman is attached to the crank-pin of the crank-wheel g , which is attached to the inner end of a short shaft, g' , mounted on suitable bearings attached to the lower side of the grain-table. A pinion, H , is also fixed on this crank-shaft and arranged so that its path will be over the segmental gears D D' . This pinion is mutilated, having toothed sections h on opposite sides thereof, between which are arranged studs or projections.

A small frame, I , is mounted by pivotal supports in pendants I' , extending downward from the under side of the table between the rim and inner flange. This frame is arranged to vibrate vertically on its pivots, which are located near the inner end thereof. Two arms or pins, i , project from the inner end of the frame and rest on the flange A' , which serves as a guide to control the position and movement of the swinging frame by means of these guiding-pins. The swinging frame extends outward over the space between the rim and flange A' , its outer end projecting somewhat beyond the former, as shown in Fig. 4 of the drawings. The twister-hook K is mounted in this swinging frame, its shaft k being arranged loosely in its bearings to permit a sliding or longitudinal movement lengthwise of the frame and in a direction radial to the revolving table. The twister-pinion L is fixed on the shaft k , and is arranged so that its path will be over the rack E as it is carried around by the revolution of the binding-table. This pinion is provided with flanges l l' on each end, the former of which is cut away to present a short straight portion, l^2 , on the side of the shaft k opposite to the point of the twister-hook. A spring, k' , is attached to the swinging frame back or inside of the twister-pinion, and arranged to press upon the back of said pinion, thereby causing the twister-shaft and twister to be thrust outward to their fullest extent in their normal position. The outer end of the swinging frame is cut away to form a shoulder, i' , in which a notch, i^2 , is made extending inward below the twister and in the direction of its shaft.

A bent arm or lever, M , is pivoted to the swinging frame, as shown in Fig. 7 of the drawings, its outer end being bent around in front of the frame, in bell-crank form, in such position that its outer extremity may be brought up against the face of the shoulder i' . This outer extremity of the arm is beveled to form a biting or clamping edge, m , which is adapted to fit the notch i^2 in the shoulder i' , for the purpose of clamping the band-wire. On the upper side of this end of the arm there is also a cutting-blade, N , which projects sufficiently to pass a short distance over the upper face of the shoulder i' , against which it cuts when the arm is closed. The inner end of the arm M is bent backward and inward until it strikes the outer face of the flange A' , being provided at its inner extremity with a friction-roller, m' ,

which runs in contact with this flange, and thereby controls the position and movement of the clamp and cutter.

A recess, b^3 , is made in the edge of the binding-table at one side thereof, directly underneath the binding-arm, through which the binding-arm passes as it descends to place the band around the bundle, and a notch, b^4 , is made in the inner edge of this recess, in which the band-wire O is received, as shown in Fig. 4 of the drawings.

The operation of this grain-binder is as follows: The binding-arm being raised or open, as shown in Fig. 1 of the drawings, and the wire run down in the notch b^4 in the recess in the edge of the table to the vibrating frame I , to which it is secured by means of the clamping device above described, a gavel is delivered upon the table, carrying back the wire underneath the binding-arm. The driving-shaft is rotated by suitable connection with the gearing of the harvester, and thus revolves the grain-table, thereby carrying the table, with the gavel thereon and binding mechanism attached thereto, around away from the delivery devices. The binding-arm remains in its raised position until the pinion H is brought to the rack-segment D , when one of the stops h' , striking against the end of the rack, turns the pinion into engagement with the rack, thereby rotating the crank-shaft and closing the binding-arm through the action of the pitman. The closing of the binding-arm carries the wire down around the bundle through the recess in the edge of the table, thereby placing another strand in the notch b^4 , which is carried down by the side of the first strand by the binding-arm as it descends to the position shown in Fig. 4 of the drawings.

It is evident that there are now two strands of wire between the end of the vibrating twister-frame and the notch in the table. About as soon as the binding-arm is closed the twister-pinion is brought into engagement with rack E , which is embraced by the flanges on the pinion. As this rack increases in thickness the pinion is drawn back as it starts into engagement with the rack, carrying the twister-hook back with it, which, at the commencement of rotation, catches the two strands of wire between the twister-frame and the table and pulls them both back with it. At the same time the twister-frame is raised at its outer end by the pinion riding up on the rack, as shown in Fig. 4 of the drawings, thereby accommodating the backward pull of the two wires and pulling wire at the same time from the spool.

The depression in the flange A' permits the guide-pins i to drop to allow the frame to be vibrated, as described. The position of the parts at this moment is shown in Fig. 4 of the drawings, and it is evident that from the clamp to the twister-hook are two strands of wire lying along the upper face of the twister-frame, and that these same two strands are continued from the hook to the edge of the table.

5 The continued revolution of the table carries the twister-pinion forward in engagement with its rack, thereby forming the twist in the ends of the wire for the purpose of securing the band around the bundle, and this twist is of peculiar form, for it is evident from the above description that double strands are twisted together, thereby forming a twist of four wires, instead of two, in the usual way.

- 10 At the last revolution of the twister the clamp is opened by the inner end of the clamp-arm dropping into the recess in the side of the flange A', thus releasing the end of the band-wire which it had held, and allowing the main wire extending upward from the binding-head to slip into the clamp, which immediately closes, thereby securing the wire, and at the same time the cutter severs it on the upper side of the frame, so as to release the bundle.
- 15 As the twister-pinion passes off from the rack the frame is turned down again by the guide-pins leaving the recess in the flange A', the twister is thrown forward by the action of the spring, the wire slips off the end of the twister, and the bundle may be discharged.
- 20
- 25

30 The rack and twister-pinion are so constructed and timed that the rotation of the latter will always cease with the twister-hook point projecting upward, as shown in Fig. 5 of the drawings, and as the pinion is thrown forward and the vibrating frame lowered the straight edge l² of the flange l rests upon the rim of the support below, as shown in Fig. 5 of the drawings, thereby locking the twister in this position.

35 The continued revolution of the table soon brings the pinion H into engagement with the rack D', thereby rotating the crank-shaft in the direction to pull down the pitman and open the binding-arm, when, of course, it is ready to receive another bundle, and the operation is repeated.

40 It will be readily understood that the parts described must be arranged with reference to the delivery mechanism of the harvesting-machine, so that the binding-arm will be opened when that side of the table is presented to the delivering devices, and will be closed and the band secured after the binding-arm has been carried around away from the point of delivery. This is a mere matter of arrangement, which will be readily understood so as to be carried out by any one familiar with the construction of harvesting-machines.

45 Having thus described my invention, what I claim as new, and desire to secure by Letters Patent, is—

1. The bed or support A, provided with rack-segments D D', in combination with a revolving grain-table, B, a binding-arm, F, mounted on the table, pitman G, and crank-shaft g, provided with the pinion H, substantially as and for the purpose set forth.

2. A revolving grain-table, in combination with a binding-arm mounted thereon, a band-twister attached to and carried by the table, and formed with a pinion adapted to be moved by a rack in the fixed platform, whereby the twister is operated by the revolution of the table, substantially as described. 65

3. The twister mounted in a vibrating frame having rear projections adapted to be operated by contact with the fixed platform, substantially as described. 70

4. The vibrating frame, in combination with the sliding twister-hook mounted therein, and mechanism for raising the frame and retracting the hook as it begins to rotate, substantially as and for the purpose set forth. 75

5. The vibrating frame provided with a wire clamp at its outer end, in combination with the binding-arm, the binding-table, and sliding twister-hook, substantially as described. 80

6. The vibrating frame, in combination with the sliding twister-hook mounted therein, flanged pinion on the shaft of the twister, and cam-rack E, substantially as described. 85

7. The cam-rack E, in combination with the flanged twister-pinion arranged on a sliding twister-shaft, and a returning-spring to thrust the twister forward when released by the cam-rack, substantially as described. 90

8. The vibrating frame, in combination with the sliding twister, flanged twister-pinion provided with a straight edge, l², and the rim of the bed or support, whereby the twister is locked when not in operation and in the position specified, substantially as and for the purpose set forth. 95

9. The combination of a vibrating frame having a clamping-shoulder at its front end, a sliding twister mounted on the vibrating frame, and a clamping-arm pivoted on the vibrating frame and coacting with the clamping-shoulder to seize the wire, substantially as and for the purpose specified. 100

10. The pivoted frame I, in combination with the clamping-arm M and cutter N, located on the clamping-arm, substantially as described. 105

11. The flange A' on the bed, provided with a side depression, a², in combination with the clamping-arm M and vibrating frame I, substantially as described. 110

12. The vibrating frame I, attached to the revolving grain-table and provided with guides projecting in rear of its pivots, in combination with the stationary flange A', provided with a cam-depression, a', in its upper edge, substantially as described. 115
